US0D1003844S

(12) **United States Design Patent** (10) **Patent No.:** **US D1,003,844 S**
(45) **Date of Patent:** **** Nov. 7, 2023**

(54) **LIVE STREAMING DEVICE**

- (71) Applicant: **Hangzhou Xingxi Technology Co., Ltd.**, Zhejiang (CN)
- (72) Inventors: **Wenbo Cheng**, Hangzhou (CN); **Yunyi Yan**, Hangzhou (CN)
- (73) Assignee: **Hangzhou Xingxi Technology Co., Ltd.**, Hangzhou (CN)
- (**) Term: **15 Years**
- (21) Appl. No.: **29/808,860**
- (22) Filed: **Sep. 23, 2021**

(30) **Foreign Application Priority Data**

- Mar. 23, 2021 (CN) 202130155932.4

(57) **CLAIM**

The ornamental design for a live streaming device, as shown and described.

DESCRIPTION

FIG. 1 is a perspective view of a live streaming device, showing our design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Broken lines seen in the drawings depict portions of the live streaming device that form no part of the claimed design.

1 Claim, 5 Drawing Sheets
